UNITED STATES PATENT OFFICE.

GEORGE W. JOHNSTON, OF WASHINGTON, DISTRICT OF COLUMBIA.

WINDOW SCREEN.

Application filed April 18, 1922. Serial No. 554,711.

To all whom it may concern:

Be it known that I, GEORGE W. JOHNSTON, a citizen of the United States, residing at Washington, in the District of Columbia, have invented certain new and useful Improvements in Window Screens, of which the following is a specification.

This invention relates to window screens, and more particularly to that type in which the screen is adapted to be stored in a pocket arranged in the wall adjacent the window frame.

The object of my invention is to so arrange a pocket window screen installation of the above type, in which the screen may be concealed or stored in the wall adjacent the window frame when not in use, and which can readily be removed from the pocket to a position to cover a window opening.

A further object is to construct a window screen in such a manner that the lower rail thereof, when the screen in its unused or stored position, forms a closure for the pocket in which the screen is stored and at the same time forms an outer bead for the upper rail of the upper sash.

A further object is to arrange a follower within the pocket which when the screen has been removed from the pocket will form a closure for the pocket so that birds, insects and the like will be excluded therefrom.

Another object is to provide a pocket window screen installation in which the screen can be removed from its guides without disturbing the pocket or guides therein.

Other objects of this invention will be made manifest in the following specification when considered in connection with the accompanying drawings, in which

Figure 1 is a front elevation of a window frame with my invention applied thereto;

Fig. 2 is a vertical sectional view on line 2—2 of Fig. 1;

Fig. 3 is an enlarged sectional view showing the screen stored in the pocket;

Fig. 4 is a transverse sectional view taken on line 4—4 of Fig. 1;

Fig. 5 is a detail perspective view of the follower;

Figs. 6 and 7 are detail views of the friction devices for retaining the screen in position upon the window frame; and

Figs. 8 and 9 are detail views of the pull-ring.

In the drawings the numeral 1 indicates a window sash of the usual construction, hav-

ing slidably mounted therein upper and lower sashes 2 and 3 respectively.

Secured in the wall 4 above the window frame is a pocket 5 provided with an opening 6 at its lower end, this opening being of less width than the pocket. Arranged in the wall above the pocket is a lintel 7, and just above the window frame on either side of the pocket 5 are lintels 8 and 9. Adapted to be received in the pocket 5 is a vertically sliding screen 10, consisting of a substantially rectangular frame, the lower rail thereof being practically the same width as the opening 6 of the pocket 5 and adapted to close the same when the screen is in its upper position. The side rails 11 of the screen are grooved as at 12, for the reception of the projecting portion 13 of the T-shaped screen guide rails 14. These guide rails 14 are arranged at either side of the window frame in alignment with the opening 6 of the pocket, and extend into the pocket to the top thereof. Secured within the grooves 12 are suitable friction devices consisting of a bowed spring portion 15 provided centrally thereof with outwardly projecting flanges 16, forming a channel to engage the projecting portions 13. These devices serve to hold the screen in any desired position upon the 75 guides.

Arranged within the pocket above the screen is a follower 17, consisting preferably of a substantially T-shaped member extending the full length of the pocket. The body portion of the follower is of substantially the same width as the pocket, and the downwardly extending portion of the follower is substantially the same width as the opening 5 of the pocket. The outer ends of the follower are grooved as at 18 for the reception of the guide rails 14. The downwardly extending portion of the follower is preferably rounded to fit the similarly rounded upper edge of the upper screen rail. As disclosed in Fig. 2 when the screen is in its lowered position, the follower 17 serves to close the opening 6 of the pocket, thereby excluding birds, insects and the like. The follower is retained within the pocket when the screen is removed therefrom, by means of the flanges 19 on the lower edges of the pocket. In this position the downwardly extending portion of the follower forms a beading for the upper rail of the upper sash.

One or both of the vertical guide rails 14

may be formed in sections in order that a section of the guide may be removed to facilitate the removal of the screen from the window frame for repairs. This will enable the removal of the screen without disturbing the guide rails which are secured in the pocket.

A casing 20 is embedded in the lower rail of the screen frame and has pivoted thereto 10 a pull-ring 21. The pull-ring 21 is provided with a rectangular portion 22 against which a spring 23, stamped from the casing, is adapted to bear for the purpose of holding the pull-ring in a position within the 15 casing or extended for use.

From the foregoing it will be seen that the screen can be stored within the pocket 5, or drawn from the pocket to cover the window opening when either of the sashes 20 are in open position.

It will be clear from the drawings that the guide rails 14 form the outer beads for the upper sash 2 and thereby permit the upper sash and screen 10 to be held in close 25 contact.

To assist in raising the screen to its upper position I have provided handles 22. These handles are secured to the upper surface of the bottom rail of the screen frame in such 30 a manner that they do not interfere with the movement of the screen into the pocket.

It is to be understood that it is not intended that the spirit of this invention should be construed as applicable only to the 35 exact structure above described due to my failure to mention alternative structures during the description. While this invention is shown applied to a window frame mounted in a brick wall it is to be understood that the invention may be used equally 40 in wood tile and other buildings.

I claim as my invention:

1. A storage receptacle for window screens comprising a pocket arranged adjacent a window and gravity operated means for closing the pocket when the same is wholly extended without said receptacle, said means also forming a seal at the upper edge of the screen when the same is in any 50 of its intermediate positions.

2. A receptacle for window screens comprising a pocket arranged adjacent a window, vertical guide members extending into the pocket, a screen adapted to slide upon the guides into and from said pocket, and a follower adapted to slide upon the guides within the pocket and adapted to close the pocket when the screen is wholly removed

from said pocket and also form a seal at the upper edge of the screen when the same 60 is in any of its intermediate positions.

3. A storage receptacle for window screens comprising a pocket arranged adjacent a window, a screen adapted to be moved into said pocket and to be either partially or wholly removed therefrom, and means contained within the pocket and co-operating therewith for closing the same when the screen is entirely removed therefrom, said means also forming a seal at the 70 upper edge of the screen when the same is in any of its intermediate positions.

4. In a building structure including a wall and opening therethrough, the combination with a closure for said opening, of a recess formed in said wall in a plane parallel to said closure, a screen adapted to slide entirely within said recess, and be extended therefrom to cover any portion of said opening, and a stop-member controlled by the 80 movements of the screen for simultaneously sealing the outer end of said recess and the upper edge of the closure when said screen is wholly extended from said recess.

5. In a building structure including a wall and opening therethrough, the combination with a closure for said opening, of a recess formed in said wall in a plane parallel to said closure, a screen adapted to slide entirely within said recess, and be extended therefrom to cover any portion of said opening, the lower edge of said screen, when the same is completely enclosed within the recess, forming a seal for the outer end of the recess and the upper edge of the closure. 95

6. In a building structure including a wall and a window opening therethrough, the combination with upper and lower sashes for said opening, of a recess formed 100 in said wall in a plane parallel to said sashes, a screen adapted to slide within and be extended from said recess to cover any portion of said opening, the lower edge of said screen forming a seal for the outer end of 105 the recess and the upper edge of the upper sash when the screen is completely enclosed within the recess, and a stop-member controlled by the movement of the screen for simultaneously sealing the outer end of said recess and the upper edge of the upper sash when said screen is wholly extended from 110 said recess.

In testimony whereof I affix my signature.

GEORGE W. JOHNSTON.
